UNITED STATES PATENT OFFICE.

ZACHARY TAYLOR COX, OF SALT LAKE CITY, UTAH.

SWIMMING APPARATUS.

No. 826,145.

Specification of Letters Patent.

Patented July 17, 1906.

Application filed January 20, 1906, Serial No. 297,046.

To all whom it may concern:

Be it known that I, ZACHARY TAYLOR Cox, a citizen of the United States, residing at Salt Lake City, in the county of Salt Lake 5 and State of Utah, have invented a new and useful Swimming Apparatus, of which the following is a specification.

This invention relates to swimming apparatus, and has for its object to provide a simple, inexpensive, and efficient device of this 10 character particularly designed for attachment to the leg or ankle of a person to assist the wearer in swimming, treading water, and performing other aquatic feats.

15 A further object of the invention is to provide a supporting - band having a flexible web secured thereto and adapted to expand and contract as the legs of the swimmer are forced forward and drawn rearwardly in the 20 act of swimming.

25 A further object is to provide the supporting-band with a pneumatic pad or cushion to prevent chafing or otherwise abrading the skin.

30 A still further object is to generally improve this class of devices, so as to add to their utility and durability as well as to reduce the cost of manufacture.

35 With these and other objects in view the invention consists in the construction and novel combination and arrangement of parts hereinafter fully described, and illustrated in the accompanying drawings, it being understood that various changes in form, proportions, and minor details of construction may 40 be resorted to within the scope of the appended claims.

45 In the accompanying drawings, forming a part of this specification, Figure 1 is a side elevation of my improved swimming apparatus, showing the web expanded and in dotted lines, the latter contracted or collapsed. Fig. 2 is a longitudinal sectional view. Fig. 3 is an enlarged detail transverse sectional view, and Fig. 4 is a similar view.

Similar numerals of reference indicate corresponding parts in all the figures of the drawings.

50 The improved devices consist of a supporting-band adapted to encircle the leg or ankle of the wearer and indicated as a whole at 5, said band being formed of leather, canvas, or other suitable material and constructed of a plurality of layers or sections 6, 7, and 8, 55 sewed or otherwise secured together at their upper ends, as indicated at 9. The adjacent

vertical edges 10 and 11 of the band 5 are yieldably connected by a thin strip of rubber or other flexible material 12, which engages the interior and exterior walls of said band, 60 as shown, while riveted or otherwise secured to the exterior walls of the band are straps 13 for engagement with suitable buckles 14.

Interposed between the layers 6 and 7 and secured to the band 5, as by rivets 15, are a 65 plurality of spaced flexible ribs 16, the free ends of which are interposed between the interior and exterior walls of a web or covering 17, preferably formed of thin sheet-rubber, as shown, there being a cord or other flexible 70 medium 18 seated in the terminal pocket 19 of the web and alternately engaging the inner and outer faces of the ribs 16 to assist in reinforcing the edge of the web when the latter is expanded.

75 To prevent the band 5 from slipping forward on the leg of the wearer, a strap 20 is secured to one end of said band, while its free end passes beneath the foot and extends upwardly through a pocket 21 for engagement with a buckle 22, secured to the adjacent exterior wall of said band.

Engaging the interior walls of the band 5 is a pneumatic pad or cushion 23, adapted to bear against the leg of the wearer so as to prevent chafing or otherwise abrading the skin, said pad being inflated by a suitable valve 24, extending through the several sections of the band and provided with a cap or closure 25, there being a strip of felt or other yieldable 90 material 26 interposed between the pad and the adjacent layer 8 to form a smooth bearing-surface for said pad.

In applying the device the straps 13 are released and the foot inserted through the band 5, the thin connecting-strip of rubber permitting the band to yield or expand sufficiently to allow the passage of the foot. The band is then adjusted longitudinally on the leg and the strap 20 passed beneath the foot and 95 secured by the buckle 22, after which the straps 13 are adjusted and fastened by the buckles 14. When the device is thus applied, a rearward movement of the legs in the act of swimming will collapse the web or covering 100 and cause the latter to offer but slight resistance to the water; but upon the forward stroke the web will expand and present a relatively large bearing-surface for contact with the water, thereby materially adding to 105 the effectiveness of the stroke and causing the swimmer to move forward at a largely-

increased speed. It is obvious that the device may be used with equally good results in treading water and, if desired, may be attached to the wrist or arm.

5. By having the supporting-band formed of a plurality of layers or sections it not only reinforces and strengthens the band, but permits the interposition of the ribs and foot-engaging strap between adjacent layers, so as to present a practically smooth unobstructed interior and exterior surface, while by having the adjacent ends of the strap connected by the strip of rubber the ends of said band are yieldably supported in contact with each other, but are free to expand to permit the passage of the foot.

If desired, the supporting-band and foot-engaging strap may be constructed of metal, such as aluminium, in which case they will be formed in two or more sections hinged together to permit the same to be conveniently positioned on the foot.

Having thus described the invention, what is claimed is—

25. 1. In a device of the class described, a supporting member, a plurality of flexible ribs carried by the member, a web covering said ribs, and a pneumatic cushion engaging the interior walls of the supporting member.

30. 2. In a device of the class described, a supporting member, a rubber band covering the interior and exterior walls of the supporting member and connecting the adjacent ends of the latter, ribs secured to the supporting member, a web covering the free end of the ribs, and attaching means for said member.

35. 3. In a device of the class described, a supporting member, a rubber band covering the interior and exterior walls of the supporting member and connecting the adjacent ends of the latter, flexible ribs secured to said member, a web covering the free end of the ribs, an auxiliary fastening means for the supporting member, and a foot-engaging strap carried by said supporting member.

40. 4. In a device of the class described, a supporting member formed of a plurality of superposed sections, ribs interposed between adjacent sections and having their free ends extended beyond said member, a web covering the free ends of the ribs, a pneumatic cushion engaging the interior walls of the

supporting member, an inflation-valve extending through the walls of the several sections and communicating with the cushion, 55 and attaching means for said member.

5. In a device of the class described, a supporting member formed of a plurality of superposed sections, ribs interposed between adjacent sections and having their free ends 60 extended beyond the member, a pneumatic cushion engaging the interior walls of the supporting member, a web covering the free ends of the ribs, a foot-engaging strap secured to one wall of the supporting member 65 and having its free end extending through a pocket in the opposite wall, and attaching means for the supporting member.

6. In a device of the class described, a supporting-band formed of a plurality of superposed sections, ribs interposed between adjacent sections and having their free ends extended beyond the member, a web covering the free ends of the ribs, a pneumatic cushion engaging the interior wall of the band, a 70 strip of yieldable material interposed between the pad and the interior wall of the band, a foot-engaging strap carried by the band, and attaching means for said band.

7. In a device of the class described, a supporting-band formed of a plurality of superposed sections having their adjacent ends connected by a strip of yieldable material, ribs interposed between adjacent sections and having their free ends extended beyond the 85 member, a web covering the free ends of the ribs and extending throughout the length of said ribs on each side thereof, a flexible medium carried by the web and alternately engaging the opposite faces of the ribs, a foot- 90 engaging strap carried by the band, a pneumatic cushion engaging the interior walls of the band an inflation-valve extending through the walls of the several sections and communicating with the cushion, and attaching 95 means for said band.

In testimony that I claim the foregoing as my own I have hereto affixed my signature in the presence of two witnesses.

ZACHARY TAYLOR COX.
